Pauline Schnittman, New York, N. Y.

Application June 28, 1937, Serial No. 70,093

Term of patent 3½ years

To all whom it may concern:

Be it known that I, Pauline Schnittman, a citizen of the United States of America, residing in Manhattan, county of New York, and State of New York, have invented a new, original, and ornamental Design for a Robe, of which the following is a specification, reference being had to the accompanying drawing, forming part thereof, wherein,

Figure 1 is a front view of a robe showing my new design.

The characteristic feature resides in the combination on the robe as shown of the short curved side seams of the top portion in association with the double button closure, said seams being trimmed with fringe to match the cuffs as shown.

I claim:

The ornamental design for a robe, substantially as shown and described.

PAULINE SCHNITTMAN.
